CLAIM

The ornamental design for a nest for precrimped presterilized cartridges, as shown and described.

DESCRIPTION

FIG. 1 is a top, left, front perspective view of a nest for precrimped presterilized cartridges showing our new design; FIG. 2 is a top plan view thereof;

FIG. 3 is a bottom, right, front perspective view thereof; FIG. 4 is a bottom, right, front perspective view thereof, with a detail portion identified for enlarged view;

FIG. 5 is an enlarged view of the detailed portion of FIG. 4; and,

FIG. 6 is a bottom plan view thereof.

The broken line showing is for the purpose of illustrating portions of the nest for precrimped presterilized cartridges and forms no part of the claimed design.
